UNITED STATES PATENT OFFICE.

FREDERICK A. SCHOSOW, OF DETROIT, MICHIGAN.

FLUSH-VALVE.

1,148,542.

Specification of Letters Patent. Patented Aug. 3, 1915.

Application filed January 22, 1915. Serial No. 3,699.

To all whom it may concern:

Be it known that I, FREDERICK A. SCHOSOW, citizen of the United States, residing at Detroit, county of Wayne, State of Michigan, have invented a certain new and useful Improvement in Flush-Valves, and declare the following to be a full, clear, and exact description of the same, such as will enable others skilled in the art to which it pertains to make and use the same, reference being had to the accompanying drawings, which form a part of this specification.

My invention relates to a flush valve shown in the accompanying drawing and more particularly pointed out in the following specification and claims.

One of the objects of my invention is to provide a device simple and inexpensive in its construction and operation capable of effecting a thorough flushing of a closet bowl or other appliance by maintaining the valve continuously open when raised until the water has been discharged from the tank controlled by the valve. This result being obtained by the water in passing from the tank acting upon means provided to maintain the valve in its open position until the water is discharged whereupon the valve automatically seats itself that the tank may again be refilled.

Another object of the invention is to provide means to insure what is known as an "after fill" following the discharge of the water through the closet bowl, whereby the water seal required in the closet bowl may be maintained.

Other advantages and improvements will hereafter appear.

In the drawings accompanying this specification:—Figure 1, is a longitudinal vertical section through a flushing tank indicating in elevation the flush valve casing and means for manually raising the valve. Fig. 2, is a vertical sectional view through the valve casing with parts broken away, showing the valve seated. Fig. 3, is a similar view showing the valve raised. Fig. 4, is a detail view in section of a modification showing in lieu of the valve controlling disk, a cup having a small perforation in its lower wall.

Referring now to the letters of reference placed upon the drawings:—A, denotes a flushing tank or water reservoir.

B, indicates a casing provided with an outlet pipe B', projecting through the wall

of the tank and threaded to receive the usual pipe connections (not shown) leading to a closet bowl or other place of delivery.

C, denotes a valve seated in the wall of the casing B, and preferably provided with a tubular stem C', to receive a guide rod D suitably supported in the wall of the casing.

C², is a closure cap screwed to the top of the tubular stem provided with a ring e to receive the hooked end of a link connecting it with an operating lever.

F, indicates an over-flow pipe of suitable altitude rising from the top of the casing B, and open at its upper end.

F', is a split ring clamped upon the upper end of the over-flow pipe and secured thereto by a bolt f.

F², is a standard preferably integral with the clamping ring in which is pivoted a bell crank lever G.

H, is a link connection between one arm of the bell crank lever and the ring e, on the closure cap of the tubular valve stem.

I, denotes a depending rod suspended from the other arm of the bell crank lever within the over-flow pipe F, fitted at its lower end with a disk I'.

I², is a spider frame or guide secured to the rod I, to maintain the rod in a central position within the over-flow pipe.

J, is a rocker arm for actuating the bell crank G.

G', is an adjustable bolt carried by the bell crank adapted to abut against the supporting standard F², to limit the movement of the bell crank lever.

K, is a bell crank pivoted in a supporting bracket secured to the wall of the tank.

L, is a link connecting the bell crank G with the bell crank K.

K', is a handle depending from the bell crank for convenience in manually raising the valve C, from its seat.

In the modification shown in Fig. 4 a cup M is provided in place of the disk I' carried on the end of the rod I.

m, is a relatively small perforation in the bottom of the cup to slowly release the water contained within the cup.

Having indicated the several parts by reference letters the construction and operation of the device will be readily understood:—To flush the closet the valve C is manually raised by pulling down the handle K' controlling the action of the bell crank levers. Upon raising the valve C,

the disk I' carried by the rod I, is lowered into the path of the water passing from the tank which bearing thereon serves to maintain the valve in its elevated position until 5 the water is discharged from the tank, whereupon the valve automatically seats itself, being guided to its seat by the guide D. The tank may then be refilled in the usual manner.

10 In order to provide for the "after fill" required to maintain a water seal in the closet bowl, I have indicated in the modification shown in Fig. 4, a cup provided with a small perforation to discharge water. 15 This cup is designed to take the place of the disk I' to maintain the valve C in its open position while water is being discharged from the tank and for a brief period thereafter, governed by the time required for the 20 water contained in the cup to pass therefrom; whereupon the weight of the valve C, overcoming the weight of the empty cup automatically returns to its seat.

Having thus described my invention 25 what I claim is:—

1. In a device of the character described, a casing having an inlet port and a discharge port, an over-flow pipe connected with the casing, a supporting member secured to the 30 upper end of the overflow pipe; a valve controlling the inlet port, a bell crank lever pivoted on said supporting member, means adapted to limit the tilting action of the lever, a link connecting one arm of the lever 35 with the valve, a rod connected with the other arm of the bell crank lever and suspended within the over-flow pipe, means carried by the rod adapted to be lowered by the lever into the path of the water passing 40 through the casing said means when acted upon by the water being adapted to maintain the valve in its open position until the water is discharged, and means for actuating the lever.

45 2. In a device of the character described, a casing having an inlet port and a discharge port, an over-flow pipe connected with the casing, a supporting member secured to the upper end of the overflow pipe, 50 an upright on the supporting member, a valve controlling the inlet port, a bell crank lever pivoted on the upright of said supporting member, the bell crank lever having a

projection, an adjustable stop mounted on the projection of the bell crank lever for engagement with said upright to limit the tilting action of the bell crank lever, a link connecting one arm of the lever with the valve, a rod connected with the other arm of the lever and suspended within the over-flow pipe, means carried by said rod adapted to be lowered by the lever into the path of the water passing through the casing, 55 said means when acted upon by the water being adapted to maintain the valve in its open position until the water is discharged, 60 and means for actuating the lever.

3. In a device of the character described, a casing having an inlet port and a discharge port, a valve controlling the passage 70 through the inlet port, a lever to raise the valve, a perforated cup connected with the lever adapted to be filled with water and to be acted upon by the water passing through the casing so as to maintain the valve in its 75 elevated position during the discharge of the main body of water through the casing and for a brief period thereafter, and thereby moving slowly automatically to valve closing position so that a relatively small 80 volume of water may subsequently pass through the casing to provide an after-fill.

4. In a device of the character described, a casing having an inlet port in its upper side at one end thereof and an outlet port in 85 its bottom at the opposite end thereof, the side walls of said casing being imperforate, a valve controlling the passage through the inlet port, means to raise the valve, means suspended from the aforesaid means in 90 alinement with the outlet port and movable toward the outlet port into the path of the water passing through the casing from the inlet to the outlet port when said valve is raised by the valve raising means, and which 95 is acted upon by the water to maintain the valve in its raised position while the water is being discharged through the casing and whereby said valve returns gradually automatically to its normal position.

100 In testimony whereof, I sign this specification in the presence of two witnesses.

FREDERICK A. SCHLOSSOW.
